UNITED STATES PATENT OFFICE

LOUIS F. GERDETZ, OF PITTSBURGH, PENNSYLVANIA

LOCKING DEVICE FOR CONVEYER PANS

Application filed September 8, 1928. Serial No. 304,781.

This invention relates to an improvement in locking devices for conveyer pans.

The invention relates to the art of reciprocating conveyers which are constructed of a series of pans arranged end to end so as to form a chute, which conveyers are used primarily or principally in the coal mining industry.

Heretofore it has been the practice to connect the pans together with slightly overlapped ends by means of bolts which pass through depending lugs carried by the overlapped ends. The ends of the pans would not be constructed just the same size because it was necessary to provide for this overlap. Consequently, the pans were not reversible and must be carefully kept in a definite relation to each other. Also, the overlapped ends of the pans would permit the coal to travel in only one direction therethrough.

At the same time, it is necessary, as the mining of the coal progresses, to almost daily move the conveyer, and in order to do this it is necessary to uncouple a large part of it at least, and in doing so the nuts of the bolts repeatedly become lost and time is consumed in either finding the nuts or supplying new ones. All of this consumes both time and material, which is wasted every time it becomes necessary to make a change in the conveyer system.

The object of the present invention is to simplify the construction of the locking device between the pans and to eliminate all loss of time and material in connecting the ends of the pans together and, at the same time, to allow the material to be directed through the conveyer in either direction, by reason of the ends of the pans being uniform in size and in perfect alignment with each other.

This is provided by arranging the pans with the ends thereof in alignment and held in proper relation by means of the yoke, which in turn is provided with clamps to hold the yoke in its proper relation to the pans or to hold the pans on the yoke.

This system also permits of suspending the pans and conveyer by means of chains from above as well as allowing it to be supported upon the usual cradles, as may be desirable.

In the accompanying drawings:

Fig. 1 is a partial side elevation of the invention as applied to a conveyer of this type;

Fig. 2 is a longitudinal sectional view therethrough;

Fig. 3 is a transverse sectional view through a pan, showing the invention in side elevation;

Fig. 4 is a sectional view on the line 4—4 of Fig. 3;

Fig. 5 is a top plan view of the end of the yoke and the clamps; and

Fig. 6 is a side elevation of the latter showing the locking tool for the clamps.

The numeral 1 indicates the pans which are arranged end to end in slightly spaced relation, as shown in Fig. 2, and at the abutting ends they are provided with angle irons 2 riveted or otherwise secured thereto. As shown in Figs. 1 and 2, the conveyer may be mounted upon a suitable cradle of well known construction, which is designated generally by the numeral 3, to allow the reciprocating or rocking action of the conveyor.

A yoke 4 of substantially U-shape in transverse cross section, as shown in Fig. 2, fits over and receives the outward flanges 5 of the angle irons 2 and holds these flanges together, which in turn holds the abutting ends of the pans in their proper relation to each other.

As shown in Figs. 3, 4 and 5, the sides 6 of the yoke 4 at the outer end of the latter carry bolts 7 which extend transversely therethrough, one end of each bolt having a head 8 thereon and the opposite end being threaded as at 9 to receive a nut 10. A cotter-pin 11 passes through the threaded end of each bolt to prevent the removal or accidental displacement of the nut or possible loss thereof.

Clamps 12 are pivotally mounted on the bolts 7 and have hooked ends 13 adapted to hook over the flaring edges of the pans 1. A tool 14 may move these clamps into proper positions over the edges of the pans by engaging shoulders 15 on the back edges of the clamps, or may engage the hooked ends 13 of the clamps to remove the latter from the edges of the pans.

The outer edges of the sides 6 are provided with grooves 16 therein to receive ribs 17.

formed on the inner sides of the clamps 12, so that whenever the bolt is tightened with the clamps in their interfitting relation over the edges of the pans, these ribs and grooves interfit with each other to maintain the 5 clamps in their proper positions and against displacement. A flange 18 is formed on the lower edge of one of the clamps 12 to abut against a side of the bolt head 8 so as to prevent the bolt from turning when the nut is being tightened or released, thus allowing the latter to be accomplished by means of a single wrench, it not being necessary to hold both ends of the bolt.

15 A spacer 19 is fitted between the sides 6 at each end of the yoke 4 through which the bolt 7 extends, as shown in Fig. 4, in order to hold the sides in properly spaced relation. The spacers 19 are provided with eyes 20 in the 20 outer ends thereof adapted to receive the hooks 21, which may be attached to supporting chains in order to allow the reciprocating conveyors to be carried by chains instead of the cradles, as shown in Figs. 1 and 2, if so 25 desired.

In using the invention to connect the ends 30 of the pans together, the yoke 4 may be mounted on the cradle 3 in the proper relation and the pans brought into position so that the outer flanges 5 of the angle irons 2 may be dropped into the yoke 4 where they hold the 35 ends of the pans in proper relation to each other. A slight space may be provided between the ends of the pans when so held, which quickly fills with coal dust and facilitates the connection of the pans together, as well as cushioning them during the reciprocation of the conveyer, and in this way providing a continuous unbroken surface in the 40 conveyer which allows of the pans being reversed since the ends are all the same.

After the pans have been dropped into place in the yoke, the tool 14 may be used to turn the clamps 12 with the hooks 13 thereof over the flaring edges of the pans and the nuts 10 may then be tightened up to hold the 45 clamps in this position, this being facilitated by the interfitting relation between the grooves 16 and the ribs 17.

50 If the conveyer is supported by chains or similar flexible devices, the spacers 19 may be turned up into the positions shown in Figs. 3 and 4, so as to receive the hooks of the chains, but if the conveyer is mounted on the cradles 55 these spacers may be turned down, as shown in Fig. 1.

The cotter-pins 11 in the ends of the bolts prevent the loss of the nuts and likewise of time in coupling up the pans.

60 This is an entirely new way of attaching the ends of the pans in reciprocating conveyers together and eliminates loss of time and material in making the connections between the pans and at the same time provides a more secure and better connection, which allows

the material to be directed in either way along the conveyer and also allows the conveyer to be suspended by chains if desired instead of on the cradles usually employed.

I claim:—

1. In a conveyer of the character described, the combination of the aligned ends of pans having flanges extending outwardly therefrom and an approximately U-shaped yoke fitted over the flanges for holding the ends of the pans in proper alignment, bolts extending through the opposite ends of the yoke, and clamps carried by said bolts and adapted to fit over the opposite edges of the pans for holding the yoke in its proper position over the flanges. 70

75 2. In a conveyer of the character described, the combination of the adjacent ends of pans, a yoke connected with said ends for holding them in proper relation and having the sides thereof in spaced relation, a bolt carried by the yoke, clamps pivotally mounted on said bolt for hooking over the edges of the pans to maintain the proper relation of the yoke therewith, and a spacer arranged between the sides of the yoke over the bolt and having an eye therein for receiving the supporting 85 means. 90

95 3. In a conveyer of the character described, the combination of adjacent ends of pans, a yoke for connecting said pans together, a bolt carried by said yoke, clamps pivotally mounted on said bolt and adapted to hook over the edges of the pans to maintain the proper relation of the yoke therewith, and interfitting means between the sides of the yoke and the clamps for holding said clamps in their clamped positions when the bolt is tightened. 100

105 4. In a conveyer of the character described, the combination of adjacent ends of pans having outwardly extending projections connected therewith, a yoke adapted to receive and embrace said projections, and means connected with an end of said yoke to hook over an edge of the pans to hold the yoke in position. 110

115 5. In a conveyer of the character described, the combination of adjacent ends of pans having outwardly extending projections connected therewith, a yoke adapted to receive and embrace said projections to hold the ends together, and a hook connected with said yoke to hook over an edge of the pans to hold the yoke in position. 120

6. In a conveyer of the character described, the combination of adjacent ends of pans, a yoke connecting said ends together, and a hook connected with said yoke and adapted to hook over an edge of the pans to hold the pan and yoke in proper relation. 125

7. In a conveyer of the character described, the combination of adjacent ends of pans, a yoke connecting said ends together, a bolt connected with an end of the yoke, and a clamp 130

carried by said bolt and adapted to fit over an edge of the pan to hold said pan and yoke in proper relation.

8. In a conveyer of the character described, the combination of adjacent ends of pans, a yoke connecting said ends together, bolts connected with the opposite ends of the yoke, and clamps carried by said bolts and adapted to hook over edges of the pans for holding said

10 pans and yoke in proper relation.

9. In a conveyer of the character described, the combination of adjacent ends of pans having outwardly extending projections connected therewith, a yoke adapted to receive and embrace said projections, means connected with the yoke and adapted to engage the pans for holding the yoke in its proper position over the projections, and locking means for holding said last-mentioned means

20 against disengagement with the pans.

10. In a conveyer of the character described, the combination of adjacent ends of pans having flanges thereon, a yoke adapted to receive and embrace the flanges, clamps connected with the yoke and adapted to engage the pans for holding the yoke in its proper position over the flanges, and locking means for holding the clamps against disengagement with the pans.

30 11. In a conveyer of the character described, the combination of adjacent ends of pans having outwardly extending flanges thereon, a yoke extending from one side of the pans to the other and having sides joined together at their outer edges and embracing the flanges to hold the pans together, and means for holding the sides of the yoke in proper relation and against spreading.

12. In a conveyer of the character described, the combination of aligned ends of pans having outwardly extending flanges on the outer sides thereof, an approximately U-shaped yoke having sides joined together at their outer edges, and embracing the flanges to hold the ends of the pans together, bolts extending through the sides of the yoke, and means in the outer ends of the bolts for holding the sides of the yoke in proper relation and against spreading.

50 In testimony whereof I affix my signature.
LOUIS F. GERDETZ.
